UNITED STATES PATENT OFFICE.

OSCAR A. ROEDELL AND ARCHIBALD W. SCHAUER, OF MINNEAPOLIS, MINNESOTA.

DUPLICATE BAGGAGE-CHECK.

1,181,482.

Specification of Letters Patent.

Patented May 2, 1916.

Application filed September 20, 1915. Serial No. 51,512.

To all whom it may concern:

Be it known that we, OSCAR A. ROEDELL and ARCHIBALD W. SCHAUER, citizens of the United States, residing at Minneapolis, in the county of Hennepin and State of Minnesota, have invented certain new and useful Improvements in Duplicate Baggage-Checks, of which the following is a specification.

10 Our invention relates to duplicate baggage checks, and has for its object to provide a baggage check particularly of the type employed in the collection of excess baggage wherein there is a considerable amount of data to be entered upon the check which is attached to the piece of baggage, and which data should be recorded upon a slip or book to go to the auditing department of the road.

20 It is the purpose of our invention to provide means whereby such an auditing slip bearing the check number and filed therewith may be filled in simultaneously with the filling-in of the check proper so that such data will need to be written but once; and because the auditing slip bears the duplicate check number there can be no mistake in the record made from the auditing slip.

30 The full objects and advantages of our invention will appear in connection with the detailed description thereof and are particularly pointed out in the claims.

In the drawings, illustrating the application of our invention in one form, Figure 1 is a front view of a baggage check embodying our invention with the auditor's slip partially removed. Fig. 2 is a section through the same. Fig. 3 is an enlarged 40 section showing the construction of the recording auditor's slip.

As illustrated the check blank 10 is provided with an attaching string 11 in the usual way, and has a removable portion 12 which is to be a passenger's identification check. On an intermediate portion 13 of the check blank appears the form which is to be filled in with the necessary data for describing and checking a package, and the auditor's slip 14 is a duplicate form which is attached to the check blank 10 so as exactly to overlie the form 13. The detach-

able identification check 12, the form 13 and the auditor's slip 14 are all provided with the same number, as indicated at 15, said 55 number appearing at the bottom of each portion in large type.

The auditor's slip 14 will preferably be formed of what is known as carbon paper on which a layer of carbon 16, as indicated 60 in Fig. 3, is applied to the portion of the slip which comes next to the form 13. It is obvious that separate carbon paper might be employed if desirable, although for the purpose of this invention the use of recording carbon paper in which the carbon is upon the rear face of the auditor's slip gives 65 the most effective results.

The slip 14 may be attached to the body 10 by eyelets 17 or in any other suitable manner such that it may readily be removed, and it will normally lie above the form 13 with the identification numbers 15 above one another on both the form and the slip. When such a check is filled in the data is 75 written upon the slip, which thus, of course, is the original record of the transaction. A copy of this writing is reproduced, however, upon the form 13 by reason of the carbon paper or carbon backing of slip 14. 80 The major part of the record is written out on the auditor's slip, there being little writing required on the passenger's identification duplicate check, so that if any error is made other than that of destination in filling in the duplicate check no damage will 85 result. The auditor's slip is then torn off, the identification check detached and given to the passenger, and the check form with the carbon copy of the auditor's slip thereon is attached to the piece of baggage. The auditor's slip is filed and forwarded to the auditor's department where the proper comparisons and recording are effected.

We claim:

A baggage check comprising a relatively stiff main portion constituting a destination check and attached passenger identification check at one end thereof with a weakened line between the main portion and such 100 check for detachment of the check, and a relatively flexible portion constituting an auditor's check superimposed upon one only of said checks, the auditor's check and one

of said other checks being provided with corresponding matter or data, and each of the three checks provided with the same identifying numerals or characters, and a
5 reproducing surface lying only between one of the checks and auditor's check, substantially as described.

In testimony whereof we affix our signatures in presence of two witnesses.

OSCAR A. ROEDELL.

ARCHIBALD W. SCHAUER.
